(57) **CLAIM**

The ornamental design for a shower head as shown and described.

DESCRIPTION

FIG. 1 is a front perspective view of a shower head showing my new design;

FIG. 2 is rear perspective view thereof;

FIG. 3 is a front view thereof;

FIG. 4 is a rear view thereof;

FIG. 5 is a left view thereof;

FIG. 6 is a right view thereof;

FIG. 7 is a top plan view thereof; and,

FIG. 8 is bottom plan view of a shower head as shown.

The broken line showing of the shower head is for the purpose of illustrating article and forms no part of the claimed design.

1 Claim, 8 Drawing Sheets
